Primary Examiner — Karen E Eldridge Powers(74) *Attorney, Agent, or Firm* — Knobbe, Martens, Olson & Bear, LLP(57) **CLAIM**

I claim the ornamental design for a case, as shown and described.

DESCRIPTION

FIG. 1 is a top end view of a case showing our new design;

FIG. 2 is a bottom end view of the case;

FIG. 3 is a left side view of the case;

FIG. 4 is a right side view of the case;

FIG. 5 is a front view of the case;

FIG. 6 is a back view of the case; and,

FIG. 7 is a back perspective view of the case.

The broken lines in the FIGURES showing the accessory holes are for illustrative purposes only and form no part of the claimed design.
